DESCRIPTION

(51) **LOC (12) Cl.** **14-02**

FIG. 1 is a bottom perspective view of a combined pen and electronic device showing my new design;

(52) **U.S. Cl.**

FIG. 2 is a front elevation view thereof;

USPC **D14/342; D14/411**

FIG. 3 is a rear elevation view thereof;

(58) **Field of Classification Search**

FIG. 4 is a left-side elevation view thereof;

USPC D14/411, 251-254, 315-318, 341-347,

FIG. 5 is a right-side elevation view thereof;

D14/420, 426, 240, 129-130, 496, 137,

FIG. 6 is a top plan view thereof;

D14/138 R, 138 AA, 138 AB, 138 AC,

FIG. 7 is a bottom plan view thereof;

D14/136 AD, 138 C, 138 G, 147,

FIG. 8 is an enlarged bottom perspective view of the portion delineated in FIG. 1; and,

D14/203.1-203.8, 218, 247, 371, 248,

FIG. 9 is an enlarged left-side elevation view of the portion delineated in FIG. 4.

D14/388-389, 374; D8/61; D19/35, 36,

The evenly spaced dashed broken lines shown in the drawings illustrate portions of the electronic device that form no part of the claimed design.

D19/77, 81-84, 115-204, 26, 59, 60;

The dot-dash broken lines shown in the drawings illustrate a boundary line that forms no part of the claimed design.

D16/208; D6/308, 310; D10/104.1, 50,

The dot-dot-dash broken lines shown in the drawings delineate portions of the claimed design in FIGS. 1, 4, 8, and 9 that are illustrated in enlarged views and form no part of the claimed design.
